To all whom it may concern:

Be it known that I, LOUIS TIM, a citizen of the United States, residing at New York, county of New York, and State of New York, have invented and produced a new and original Design for a Shirt Envelope or Holder, of which the following is a specification, reference being had to the accompanying drawing, forming part thereof.

10 The leading features of the design consist in the configuration of the display-opening and the ornamentation of the face of the envelope or holder around such opening.

15 A is the envelope or holder adapted to contain a laundered shirt, and A' an elongated display-opening in the face of the envelope.

The upper end of the display-opening is approximately semicircular in form, as shown. The face of the envelope is provided with the pictorial representation of a coat D and waist-coat D', which form an ornamental border around the display-opening.
